UNITED STATES PATENT OFFICE

JOHN I. HULL, OF SCHENECTADY, NEW YORK, ASSIGNOR TO GENERAL ELECTRIC COMPANY, A CORPORATION OF NEW YORK

MOTOR SPEED CONTROL APPARATUS

Application filed May 17, 1930. Serial No. 453,339.

My invention relates to the speed control of electric motors and more specifically to the speed control of electric motors employed to drive textile machinery such as spinning machines and the like.

The principal object of my invention is to provide a controller which will receive at least one motion from a moving element on the spinning machine, transfer this motion to a movable controller member and convert the motion of this member to a regulating motion having such characteristics that its application to the speed adjusting means such as the brush shifting device of the spinning machine motor causes the motor speed to vary in a substantially constant ratio to the movement of the controller member.

Another important object of my invention is to provide a controller for operating the brush shifting device of the spinning machine motor in such a manner that the speed of the spinning machine is varied in a predetermined manner according to the position of the yarn on the bobbin.

An additional object of my invention is to provide the controller with adjusting devices whereby the spinning machine can be operated with different forms of spinning cycles to suit varying qualities of yarn, varying degrees of humidity, etc. without requiring the interchange of new parts or requiring more knowledge than is possessed by the average operator. A further object of my invention is to provide a brush shifting device for the spinning machine motor which will act in conjunction with the controller to produce the desired speed variations in the spinning machine, the brush shifting device and controller to be so constructed that the brush shifting device can be moved to a temporary position independently of the controller position so as to start the motor with minimum starting current and after the motor has accelerated the brush shifting device may be returned to the position determined by the controller. An additional object of my invention is to provide means for shifting the brushes to obtain desirable motor operating characteristics with either direction of rotation and means that will automatically

cause the motor to run in that direction of rotation for which the shifting of its brushes gives desirable operating characteristics. Other objects of my invention will become evident as this specification progresses.

I prefer to describe my invention in connection with a ring spinning machine driven by a brush shifting alternating current motor because of the relatively large number of ring spinning machines as compared to other types, the peculiar spinning cycles required by ring spinning machines and the prevalence of alternating current as a supply source, but it will be evident that my invention can be applied to other types of motors and textile machinery with beneficial results.

The operation of my invention with its resulting advantages will be best understood from the following description when considered in connection with the accompanying drawings. I have not illustrated any parts of spinning machines since they are old and well known to those skilled in the art and my invention does not depend on their particular construction. In order to assist in the description of my invention I will refer to that portion of the spinning machine which causes the reciprocating motion of the ring rail as the traverse mechanism and that portion which causes the advancement of the ring rail as the builder mechanism. The features of my invention which are believed to be novel and patentable will be pointed out in the claims appended hereto.

Fig. 1 represents an ideal filling wind spinning cycle of a rail ring spinning machine. Fig. 2 represents comparative curves showing the relation between the controller received motion and the resulting speed changes of the spinning machine with my controller and the usual type of controller. Fig. 3 represents part of my controller mechanism and brush shifting device in a simplified form so as to more readily describe how I produce speed changes which have a substantially constant ratio to the controller received motion and how I may vary that ratio. Fig. 4 represents a perspective view of my controller and brush shifting device. Fig. 5 represents the electrical connections

of the motor in conjunction with means to automatically cause the motor to rotate in the desired direction with improved operating characteristics. Fig. 6 represents an enlarged detail drawing of that portion of the controller which converts the controller received motion into the controller regulating motion to be applied to the brush shifting device and this figure also shows the means for changing the ratio of these two motions. Fig. 7 represents a top sectional view of the assembly of the shifting yoke and movable brush yokes of the driving motor together with the means used to prevent appreciable friction or misalignment during the movements of the brush yokes. Fig. 8 represents an enlarged detail drawing of the means used to guide the operating yoke of the brush shifting mechanism in the desired manner. Fig. 9 represents an enlarged detail drawing of a preferred form of coupling used between the traverse cam of the controller and the traverse mechanism on the spinning machine. Fig. 10 represents a preferred form of locking means used to prevent vibration and similar forces from changing the relative position of two of the controller members.

In Fig. 1 the abscissa represents the time required for winding one bobbin, the exact time being omitted as immaterial for our discussion, and the ordinate represents spinning machine speeds and therefore also represents bobbin speeds as the bobbins are driven at speeds directly proportional to the speed of the spinning machine. The usual spinning machine is operated at a constant speed whose value is such that the yarn tension never exceeds a permissible value. Thus if, during the winding of the bobbin, A represents the speed during some part of the spinning cycle which cannot be exceeded without excessive yarn tension, then a constant speed spinning machine should not be operated in excess of the speed represented by A and the production is proportional to the area included under A. The yarn tension varies when the spinning machine is driven at constant speed and it has long been recognized that both production and quality of yarn can be improved by driving the spinning machine at varying speeds to result in a substantially constant yarn tension during the spinning and this requires the ideal spinning speed cycle shown for example by the full line curves in Fig. 1. Both theory and experiments indicate that to operate in accordance with the ideal spinning cycle the spinning machine should be operated at a substantially constant speed during a part of the formation of the conical base as for example represented by the speed A during the region B. During the formation of the remainder of the conical base represented by C the speed is raised and lowered with each layer, the maximum speed being increased with each layer but the minimum speed remaining at A, the operating speeds being shown by the full lines S². After the completion of the conical base the speeds are raised and lowered with each layer, the maximum and minimum speeds being increased equal amounts with each layer as shown by S³ during the range D, thus operating at higher speeds without materially changing the speed variation per layer. During the next range represented by E the speeds are represented by S⁴ and it can be seen that the speeds are raised and lowered with each layer but the maximum speeds and the speed variation per layer are not materially changed, whereas in the final range represented by F it is usually desirable to raise and lower the speed with each layer and also gradually reduce the maximum speeds without materially altering the speed variation per layer, these speeds being represented by S⁵. The increased production is represented by the area included between the dotted portion of A and the full line curves S², S³, S⁴ and S⁵. It is evident however that varying qualities of yarn, varying degrees of humidity, etc., require various forms of spinning cycles to obtain the ideal spinning cycle for the particular operating condition, and thus it became desirable to devise a controller provided with means for quickly changing any or all portions of the spinning cycle without requiring the interchange of new parts and consequent interruption of operation and without requiring more knowledge than is possessed by the average operator. Various controllers have been devised but some resulted in an operation in which the spinning cycle ranges B and C would be represented by S' and S² thus decreasing production and quality and none of these controllers provided means for obtaining the ideal spinning cycle and at the same time permit any portion of the cycle to be changed without the interchange of new parts. My controller provides means for obtaining the ideal spinning cycle with different operating conditions without the interchange of new parts.

Additional reasons why heretofore built speed control devices did not accomplish the desired results is the fact that they mostly centered around the use of a controller for shifting the brushes of a series characteristics alternating current motor without giving attention to the relation between the controller movement and the resulting speed changes. The speed changes of the series characteristics motor are not strictly proportional to the brush shift and since different relative brush positions are necessary when the spinning cycles are changed for different operating conditions it was not possible to obtain ideal spinning cycles with different operating conditions unless the controller parts were changed. In addition, when compared to the

shunt characteristics alternating current motor, the speed of the series characteristics alternating current motor changes more for a given change of voltage or friction in the spinning machine and also it takes more time to make a given change in speed, thus tending to decrease production and quality. This question of production is so important that many mills keep a graphic chart of the speed

10 and it therefore became desirable to provide a drive which avoids the above described disadvantages. I, therefore, prefer to use a shunt characteristics brush shifting alternating current motor, such as is described in Re-issue Patent No. 14,031, Schrage, Dec. 14, 1915, and in addition I provide a controller which shifts the brushes in such a manner as to secure speed changes which have a substantially constant ratio with the resultant 20 received motion imparted to the controller from the spinning machine.

The usual Schrage motor consists of a rotating primary winding connected to the supply source and a rotating commutated winding on whose commutator rest movable brushes and stationary secondary windings having the ends of each phase connected to the commutator brushes. It is customary to change the speed of the motor by shifting the brushes 30 in opposite directions at equal or nearly equal speeds. I will assume for example that the motions imparted to the controller by the spinning machine give a controller received motion of 9 inches which is capable of shifting the brushes 180 electrical degrees and that synchronous speed represented by J occurs 35 at the center of this movement as shown in Fig. 2. It follows that a movement of the controller of 4.5 inches in one direction from center or synchronous speed position shifts 40 the brushes 90 electrical degrees to give minimum speed below synchronism as shown by J', whereas a movement of 4.5 inches in the opposite direction shifts the brushes 90 electrical degrees to give maximum speed above 45 synchronism as shown by J''. If the controller received motion is imparted to the brush shifting device so that the angular shift of the brushes is proportional to the 50 controller received motion, then GG would represent the relation between the brush shift and the controller received motion, and the relation between the motor speed and the controller received motion will be represented by 55 the portions of the sine curve HH, because the speed change of the Schrage motor is substantially proportional to the sine of the brush shift angle from synchronous speed position. If the controller received motion is 60 converted into a controller regulating motion whose relation to the controller received motion is represented by the portions of the sine curves KK, then the relation between the speed and the controller received motion will 65 be represented by the straight line GG. This

relationship results in the smallest brush shift angle for a given controller received motion at synchronous speed and the largest brush shift angle for a given controller motion at maximum and minimum speeds. 70 Thus I aim to obtain speed changes having a substantially constant ratio to the controller received motion which results in uniform operating conditions.

In Fig. 3 I have represented parts of my controller and brush shifting mechanism in simplified form to better show how I obtain this constant ratio and how I can change its numerical value. In Fig. 3, L represents the operating member to which is imparted the resultant received controller motion and which can move only in a vertical direction; M represents a gear on which is mounted a roller N which is adjustable as to its distance from the center of the gear; P represents a rack in mesh with the gear and P has an anti-friction roller R in contact with the shifting yoke S which moves the brush yokes T by the driving pins U, thus shifting the brushes V upward around the commutator W, whereas their movement downward is brought about by gravity when P moves downward. Assume that when L is at the position A as shown in Fig. 3, it corresponds to the brush position resulting in synchronous speed and that the movement of L from A to D corresponds to that half of its travel which results in operation below synchronous speed. Let us space AD into three equal parts as 95 shown and assume the roller N at the position E. It can be seen that the movement of L from A to B, to C and to D will result in corresponding positions of the roller N at F, G and H, thus resulting in angular movements of N corresponding to I, J and K. The angle K is larger than the angle J which in turn is larger than the angle I and if the vertical motions of L is plotted as the ordinates against the angular motions of N as abscissa, the relation will be represented by a sine curve since the vertical motion of L is equal to the vertical motion of N and is therefore proportional to the sine of the angular motions of N. As P meshes with M it follows 100 that the same relation will exist between the motion of P and the vertical motion of L. In operation the brush yokes are seldom moved more than 30 mechanical degrees from synchronous speed position to give maximum 105 or minimum speeds and thus the angular movements of the brushes will be substantially proportional to the motion of P. As the smallest angular motion of N for a given motion of L occurs at synchronous speed, it 110 follows that the relation between the brush shift angle and the motion of L will be represented by KK in Fig. 2 and thus the relation between the motor speed and the motion of L will be represented by GG in Fig. 2. It is evident that the same will be true when 115 120 125 130

L moves down to cause operation above synchronism. The controller regulating motion of P will be substantially proportional to that angle whose sine is proportional to the controller received motion of L. With the roller N at the distance from the center of M as shown by the position E there will be a certain ratio between the motions of P and L, and therefore a certain ratio between the 10 motor speed change for a given motion of L, these ratios remaining constant over the entire speed range.

If the roller N is moved inward, as for example to E', the movement of L from A to 15 B, to C and to D will result in corresponding positions of the roller N at F', G' and H' and angular motions of N corresponding to I', J' and K'. The angle K' is larger than the 20 angle J' which in turn is larger than the angle I', but the angles K', J' and I' are larger than the corresponding angles K, J and I. The relation between the motions of P and L will be the same as with the roller N at E but the ratio of their motions will be 25 greater and therefore a greater speed change will result for the same given motion of L assumed with the roller N at E. If the roller N is moved outward to the position E'', the 30 relation between the motions of P and L will remain unchanged but the ratio of their motions will be decreased from the ratio existing with the roller N at E and thus a smaller speed change will result for the same given motion of L assumed with the roller N at E.

Having outlined the basic principles of my invention in so far as they relate to the controller I will now describe a preferred construction of my controller and brush shifting device and their operation.

In Fig. 4, 10 represents the traverse cam receiving its motion from the traverse mechanism of the spinning machine through the coupling 11 and the shaft 12 which is connected to the traverse mechanism of the spinning machine, whereas 13 represents the builder cam receiving its motion from the builder mechanism of the spinning machine through the shaft shown protruding through this cam, which shaft is driven by the pulley 14 to which the cable 15 is fastened by the pin 16, one end of the cable 15 being connected to the builder mechanism and the other end being connected to one end of the spring 17 which has the other end fastened to some stationary point. The beams 18 and 19 respectively carry the rollers 20 and 21 engaging the contours of the cams 10 and 13 respectively. The beams 18 and 19 are pivoted in each other by the fulcrum block 22. A pin 23 is fastened to the beams 18 and a spring 24 is fastened between the pin 23 and the bent down ends of the beams 19 so as to always be in tension and it is evident that as the cams 10 and 13 rotate the beams 18 and 19 will move as a unit because the tension of the

spring 24 always keeps the upper edges of the beams 19 against the pin 23.

Although illustrated in Fig. 4, the following parts will be better described and understood from the detail drawing Fig. 6 in 70 which it can be seen that the fulcrum block 26 is pivoted in notches on the upper edges of the beams 18. The screw 25 has a shoulder 25' of which one face rests on 26 and the gear 27 assembled on the end of 25 rests against the 75 other face of the shoulder 25'. The screw 25 projects through the hole in 26 with a slight clearance and the lower end of 25 is threaded into the operating member 28. A bolt 29 is screwed into the internal thread of the screw 80 25 and a nut 30 locks both 27 and 29 to 25. The operating member 28 is permitted to move vertically only because it slides on the vertical stationary shaft 31 which has a slot 32 in which slides the pin 33, thus preventing circular movement of 28 around 31. 28 engages a roller 34 mounted on the block 35 of which one face rests against the gear 36 in mesh with the rack 37 which can move vertically only because it has a slot fitting the tongue of the 85 vertical stationary part 37'. The principles of operation and the results obtained as discussed in connection with Fig. 3 also apply to Fig. 6 because in Figs. 3 and 6 the following parts respectively correspond, L and 28, 90 M and 36, N and 34, P and 37. During operation it is necessary that 35 and 36 rotate as a unit so that movement of 34 causes movement of 36 and vice versa, but it should also be possible to change the distance between the 95 centers of 34 and 36 without permitting vibration and similar forces from effecting such change. These results are accomplished in the following manner. As more clearly 100 shown in Fig. 4, the slot in the block 35 fits over the angle piece 38 fastened to 36 by rivets 39. Referring again to Fig. 6, the stationary pin 40 has a shoulder 41 and on the small end of 40 there is a loose sleeve 42 welded to a handle 43 which is near the other face of 35. A bolt 44 is threaded into the small end of 40 and the sleeve 42 fits between the shoulder 41 and the head of bolt 44 with a very slight clearance. The sleeve 42 has an external thread fitting into a similar internal thread in the gear 36 and assuming these as right-hand threads it can be seen that moving 43 clockwise rotates 42 which can move axially only its clearance, thus causing 36 to advance on the thread of 42 until 35, 36 and 43 are tightened together so as to move as a unit, and to free 35 from 36 it is merely necessary to move 43 counterclockwise. To change the distance between the centers of 34 and 36 there is threaded into 35 a screw 45 having a shoulder and a small end to which is fastened the knurled wheel 46 having another shoulder, the two shoulders being on opposite sides of 38 so that turning 46 changes the 115 distance between the centers of 34 and 36 120

125

130

when 35 is freed from 36 by moving lever 43 counterclockwise, whereas moving 43 clockwise tightens 35 to 36, thus preventing movement of 46 and preventing vibration and similar forces from changing the distance between the centers of 34 and 36.

Referring again to Fig. 4, it will be seen that meshing with gear 27 there is an intermediate gear 47 rotated by the small gear 48

10 which is turned by the knurled wheel 49 and thus I can adjust the relative positions of 25 and 28. On the rack 37 there is mounted an anti-friction roller 50 on which rests the operating yoke 51 having two bosses 52 on which 15 rest driving pins 53 fastened to brush yokes 54 and 55. The yoke 54 carries the brush holders and brushes 56, 56' and 56'' and also the lug 57 for closing the switch blade 58 against the compression spring 59 and thus 20 short circuit the contacts 60 when 54 reaches a predetermined position. The yoke 55 carries the brush holders and brushes 61, 61' and 61'' and the lug 62 for closing the switch blade 63 against the compression spring 64 25 and thus short circuit the contacts 65 when 55 reaches a predetermined position. The plate 66 is fastened to the motor housing by three bolts 67 threaded into the housing and passing through clearance holes in the plate 30 66. The purpose of the three jack screws 68 will be described later. The boss 69 on the plate 66 limits the upward travel of 28 and 29. The hubs of the brush yokes 54 and 55 slide around a machined surface on the motor 35 housing while the operating yoke 51 has an opening 70 whose two parallel faces slide on the outside diameter of the hub of brush yoke 54, the length of 70 being greater than its width so as to permit 51 to move radially and 40 angularly and retain contact with the hub of 54. The operating yoke 51 has an elongated slot 71 through which protrude two bolts 72 threaded into the plate 73 and on the ends of these bolts there are rollers 74 in contact with 45 the contour of the cam plate 75 fastened to the stationary boss 76 by a bolt 77. The cam 75 has a slot 78 which fits over a stationary pin thus making 75 rigid and to the top of 75 there is secured a plate 79 by means of bolt 50 80. The plate 79 is secured to the motor housing by bolt 81 and the plate 79 has an additional bolt hole 82, two elongated slots 83 and 84 and two stamped arrow marks. To the operating yoke 51 there is fastened a 55 clevis 85 to which is secured a rod 86 on which there is screwed the knob 87.

The assembly of the yokes 51, 54 and 55 and the plate 66 are more clearly shown in Fig. 7 in which similar parts to those shown 60 in Fig. 4 are represented by the same numbers, the additional parts being the motor housing 88 and the commutator 89. It can be seen that the operating yoke 51 slides on the outside hub diameter of brush yoke 54 where- 65 as brush yokes 54 and 55 slide on the finished

surface of the motor housing. It is very important that these three yokes operate with practically no axial clearances and slide with negligible friction because friction will cause sluggish response to required speed changes 70 in the motor with resulting imperfect spinning cycles whereas noticeable axial clearances results in tilting of the yokes with harmful effects on speed and power factor regulation. The internal hub diameters of the yokes are 75 made appreciably larger than the corresponding housing diameters, thus eliminating friction from those surfaces and no harm results from these clearances because gravity always keeps those clearances at the bottom. It is desirable to manufacture these 80 yokes and housings without resorting to small tolerances in the machining of the housing and yokes and quickly assemble the yokes on the housing without appreciable axial clearances and without appreciable friction in the movements of the yokes. These results are obtained by making the combined width of the hubs of brush yokes 54 and 55 such that when the hub of 54 rests against the shoulder 85 on the housing 88 the hub of 55 will project slightly beyond the end of the housing. The plate 66 will rest against the face of the projecting hub and by moderately tightening the bolts 67 which fasten the plate 66 to the 90 housing 88 the plate 66 will bear with even tension against the hub face of yoke 55. The three jacking screws 68 are threaded into the plate 66 and their ends rest against the housing 88 and by tightening the screws 68 against 95 the housing 88 I remove the tension existing between the plate 66 and the hub of yoke 55 without any noticeable axial clearances. 100

A clearer understanding of the mechanism used for guiding the shifting yoke 51 may be 105 obtained by examining Figs. 4 and 8 together, the similar parts in both figures being represented by the same numbers. In Fig. 8 it can be seen that the slot 78 of the cam 75 fits over the pin 90 and the bolts 72 are 110 threaded into the plate 73 whose threaded holes are so spaced that the rollers 74 assembled on the ends of bolts 72 will roll along the contour of the cam 75 without appreciable friction. 91 represents cotter pins to retain 115 the rollers 74 in place.

A clearer understanding of the operation of the controller and brush shifting device will be obtained when their operation is described in connection with both Figs. 4 and 120 5 and therefore I will now describe Fig. 5 in which similar parts to those shown in Fig. 4 are represented by the same numbers. In Fig. 5 the motor 92 preferably has a rotatable primary winding 93 which may be connected 125 to the alternating current source 94 by the collector rings 95, brushes 96, either of electromagnetically operated switches 97 or 98, and main switch 99. The commutated winding 100 is preferably rotatable and is con- 130

5 nected to the rotatable commutator 89 on which rest the brushes as shown. The brushes are connected to a preferably stationary secondary winding 101. I have assumed
 10 a two-pole machine with the commutator brushes in the position corresponding to maximum speed above synchronism and therefore I have represented the ends of each secondary phase connected to brushes separated
 15 180 mechanical degrees. The switches 97 and 98 are respectively operated by solenoids 102 and 103 the movable cores of which respectively carry contact making strips 104 and 105. The remote control switches 106 and 107 have stop push buttons 108 and 108' which normally short circuit the contacts 109 and 109' due to the tension of springs 110. The solenoid switch 102 has holding contacts 111 and positive interlocking contacts 112 and either of these contacts may be closed by the strip 104. The solenoid switch 103 has holding contacts 113 and positive interlocking contacts 114 and either of these contacts may be closed by the strip 105.
 20 25 The following description of the operation of the brush shifting device is to be considered in connection with Figs. 4 and 5. In a copending application Serial No. 410,197, assigned to the same assignee of this invention, I have fully described the underlying principles for shifting the commutator brushes in the manner described therein and as I utilize the same principles in the brush shifting device described in the present application a brief description thereof will suffice. The cam plate 75 may be considered as having three operating sections represented by X, Y and Z in Fig. 4. The sections X and Z are radial with respect to the center of the commutator and their directions are respectively perpendicular to a line drawn between the pins 53 when the rollers 74 respectively operate over the sections X and Z which will hereinafter be referred to as radial sections.
 30 35 40 45 The section Y is the arc of a circle whose center is the pin 53 fastened to the brush yoke 55 when the positions of the brush yokes 54 and 55 correspond to approximately synchronous motor speed. The section Y will hereinafter be referred to as the circular section since in theory it should be circular in form although in practice it may vary somewhat from the circular form. I have assumed that the section X corresponds to supersynchronous operation and therefore the cam 75 is so positioned that when the rollers 74 operate over the section X the voltage injected by the commutated winding 100 into the secondary windings 101 will have a speed regulating component and possibly a slight power factor correcting component since with operation above synchronism the motor power factor is inherently high. To obtain the proper voltage components with variations in the me-
 50 55 60 65 chanical structure of the yokes 51, 54 and 55

and variations in the windings 100 and 101, I have provided the slot 71 so that the brush axis may be shifted in its relation to the axis of the winding 101. It is evident that when the rollers 74 operate over the section X the brush yokes 54 and 55 will be shifted in opposite directions at substantially equal velocities and there will be good motor power factor with speed regulation above synchronism. Sufficient upward movement of 51 causes the rollers 74 to move to the section Y and during operation over this section the brush yoke 55 remains stationary since the section Y is the arc of a circle whose center is the pin 53 fastened to 55 but the yoke 54 moves at substantially double the velocity it would have if both yokes 54 and 55 moved because the motion imparted to 51 is substantially half way between the pins 53 and one of these pins is stationary. With operation over the section Y the motor will run at approximately synchronous speed and the total brush shift and hence the change in speed for a given movement of 51 will be substantially the same as with operation over the section X, thus not disturbing the relation between the movement of 51 and the resulting speed change and also serving to quickly establish a power factor correcting brush axis for operation over the section Z which corresponds to sub-synchronous operation with lower inherent power factor. When the roller 74 operates over the section Z the brush yokes 54 and 55 will be shifted in opposite directions at substantially equal velocities with good motor power factor and speed regulations below synchronism.
 70 75 80 85 90 95 100 105 110 115 120 125 130 135
 Assume the controller and brush shifting device to be in the positions shown in Fig. 4. To start the motor 92 the switch 99 is closed and the yoke 51 pulled up by the knob 87. The brush yokes 54 and 55 will be brought to their minimum speed position and they will be so guided that the yoke 54 will be higher than the yoke 55 thus causing the lug 57 to close the switch blade 58 which completes the circuit from the source 94 through the contacts 60, 109 and 114 and the solenoid 102, thus energizing 102 and closing the switch 97. Assuming correct connections to the brushes 96 the motor 92 will start in the direction for which the position of the cam plate 75 gives good power factor and I have for example represented that rotation by the arrows stamped on 79. It is evident that the motor is started with the minimum starting current and without disturbing the position of the rack 37. When the motor has sufficiently accelerated the yoke 51 is lowered so it again rests on the roller 50 and although the lowering of the yoke 54 opens the contacts 60 the motor continues to run because when the solenoid 102 closed the switch 97 the strip 104 short circuited the contacts 111

and the solenoid 102 remains energized through the contacts 109, 111 and 114.

It is often required to spin the yarn with a reverse twist and therefore it is desirable to provide means that will shift the axis of the commutator brushes so as to give good power factor in the reverse direction of motor rotation and simultaneously bring about this reversed rotation and thus the motor would always run with a good power factor. To accomplish these results the knob 87 and the bolts 77 and 81 are removed and the cam 75 is slid upwards so that its slot 78 is disengaged from the pin 90 (see Fig. 8). The cam 75 is then turned 180 degrees and reassembled with the slot 78 again engaging the pin 90, the cam 75 is fastened to the boss 76 with the bolt 77 threaded into the other hole on the boss 76, the plate 79 is fastened to the housing by the bolt 81 utilizing the bolt hole 82, the rod 86 now protrudes through the slot 84 and the knob 87 is reassembled on 86. Assuming the switch 99 closed the motor 92 is started by pulling the yoke 51 up by the knob 87 and it is obvious that the brush yokes 54 and 55 will be brought to their minimum speed position and they will be so guided that 55 is higher than 54 thus causing the lug 62 to close the switch-blade 63 which completes the circuit from the source 94 through the contacts 65, 109' and 112 and the solenoid 103, thus energizing 103 and closing the switch 98. By tracing out the connections it will be seen that two of the leads from the source 94 to the brushes 96 have been interchanged and thus the motor will start in the reverse direction which will be correctly shown by the reversed positions of the arrows on the plate 79. It is evident that the motor will be started without disturbing the position of the rack 37 and when the motor has sufficiently accelerated the yoke 51 is lowered so it again rests on the roller 50 and although the lowering of the yoke 55 opens the contacts 65 the motor continues to run because when the solenoid 103 closed the switch 98 the strip 105 short circuited the contacts 113 and the solenoid 103 remains energized through the contacts 109', 113 and 112. The new position of the cam plate 75 is such that its section Y is the arc of a circle whose center is the pin 53 fastened to the brush yoke 54 when the position of the yokes 54 and 55 correspond to approximately synchronous speed and this shift in brush axis causes the motor to operate with good power factor in the reversed direction of rotation. When running in either direction the motor can be shut down by opening switch 99 or by operating the appropriate stop push button 108 or 108' or by operating some arrangement which opens both push buttons at once. The purpose of the positive interlocking contacts 112 and 114 is to prevent the closing of switch

98 unless switch 97 is open and vice versa, because should both switches be closed at the same time it would result in a short circuit of the source 94.

The following description of the operation of the controller is to be considered in connection with Figs. 1 and 4. The cam 10 makes one revolution for each layer of yarn on the bobbin and the cam 13 makes slightly less than one revolution for the entire spinning cycle. The movements of the cams 10 and 13 are combined into a resultant received motion which raises and lowers 28 and 29. The yokes 51, 54 and 55 are so positioned that their weight tends to move them downward. The raising of 28 raises 34 thus rotating 35 and 36 clockwise and raising 37 and 51 which results in shifting the brush yokes 54 and 55 upward, whereas the lowering of 28 permits gravity to move the yokes 51, 54 and 55 downward, thus causing 37 to move downward and rotate 35 and 36 counterclockwise and therefore 51 is always in contact with 50 and 34 is always in contact with 28. It is therefore evident that there will be no lost motion in the operation of the controller or brush shifting device, thus resulting in consistent and satisfactory operation over long periods of usage. I prefer to describe the motion of 37 as the regulating motion since it is the motion which is finally applied to 51 and from the descriptions accompanying Figs. 2 and 3 it will be evident that the controller received motion of 28 is converted into a controller regulating motion of 37 which will be substantially proportional to that angle whose sine is proportional to the motion of 28 in accordance with the principles discussed in connection with Fig. 3. The expressed relations between the motions of 28 and 37 will be unaffected by the shape of the cams 10 and 13, the direction of speed of rotation of the cams 10 and 13 or the position of the roller 34. If it is desired to regulate the motor speed only in response to the motion of the spinning machine traverse mechanism this may be obtained by having cam 13 stationary or by having 13 circular in form and allowing it to rotate, whereas if it is desired to regulate the motor speed only in response to the motion of the spinning machine builder mechanism this may be obtained by having cam 10 stationary or by having 10 circular in form and allowing it to rotate. In all cases the controller received motion will be represented by the motion of 28 and the expressed relation between the motions of 28 and 37 will be unaffected.

The following serves to describe the controller operation during the ideal spinning cycle shown in Fig. 1 and the changes in the spinning cycle produced by the adjusting devices of the controller. Assume that the traverse and builder mechanism of the spinning

- machine are in their proper positions for the beginning of a spinning cycle and therefore this will also be true of the positions of the cams 10 and 13. To operate at the minimum operating speed A during the range B the bolt 29 is adjusted upward by hand wheel 49 to a slightly greater extent than is necessary to maintain it in contact with 69 during the rotation of the cam 10 and the motor being properly adjusted will 10 operate at the speed A because during the range B the rotation of the cam 10 and the gradual movement of 13 results in no movement of 28 and thus no shifting of the yokes 54 and 55. No damage to the controller parts 15 will result from this stationary position of 28 because while those ends of the beams 18 and 19 which carry the rollers 20 and 21 are moved upward the other ends of the beams 20 are depressed as they swing around the fulcrum blocks 22 and 26, thus extending the spring 24 which serves to retain the unity 25 of the controller. As the spinning cycle progresses the gradual rotation of 13 gradually lowers the roller 21 so that during the range C increasing portions of the rotation 30 of the cam 10 are accompanied without any contact between 29 and 69, thus retaining the minimum speed A but giving increasing speed variations above A as shown by the 35 full line curves S² in the range C. With further progress of the spinning cycle the movement of 13 gradually lowers the roller 21 so that during the range D the bolt 29 is no longer in contact with 69 and therefore 28 40 travels the full resultant received motion, and with a gradual lowering of the roller 21 the motor speeds are represented by the curves S³ in the range D and it can be seen that the speed variation remains constant 45 for each succeeding layer of yarn although the maximum speeds are increased. During the range E the shape of the cam 13 is such that the roller 21 remains at the same elevation and thus the speed variation is constant with each layer of yarn without any change in the maximum speed as shown by the curves S⁴ in the range E. During the final range F it is usually desirable to make 50 the shape of the cam 13 such that the roller 21 is gradually raised and thus the speed variation is constant for each layer of yarn and the maximum speeds are decreased. On completion of the spinning cycle the builder 55 mechanism on the spinning machine is returned to its starting position, thus tending to slacken the cable 15 but the tension of the spring 17 pulls the cable back, thus also returning the cam 13 to its starting position. 60 During operation the following spinning cycle adjustments are possible without the interchange of parts. Adjustment of the bolt 29 limits the upward movement of 28 and hence also limits the upward movement of 37, 65 thus determining the position of the speed

line A in the region B which in turn influences the shape of the speed curves in the region C. Turning the wheel 49 raises or lowers 28 and 37 which respectively increases or decreases the speed of all parts of the spinning cycle 70 including the speed A equal amounts, thus changing the actual speeds without changing the speed variation with each layer of yarn or the shape of any part of the spinning cycle. Turning the wheel 46 does not affect the expressed relationship between the motions of 75 28 and 37 but it does change the ratio between the motions of 28 and 37 thus altering the magnitude but not the characteristics of the speed variations brought about by the controller. By adjustment of any or all of these 80 adjusting devices on the controller the spinning cycle can be readily changed without the interchange of parts so as to operate with the ideal spinning cycle with various qualities of yarn, varying degrees of humidity, etc. 85

Notwithstanding all possible care, slight variations in the motor construction might occur resulting in slight variations in its inertia and its sensitiveness of speed change and 90 in addition the inertia of the spinning machine varies with the number of bobbins, mechanical construction, etc. It should therefore be possible to easily change the relative positions of the traverse cam 10 and the element which drives it from the traverse mechanism of the spinning machine so as to readily secure the correct relationship between the speeds and the yarn position on the bobbin necessary for the ideal spinning cycle. 95 This is accomplished by the coupling 11 shown in Fig. 4, a detail drawing of which is shown in Fig. 9 in which similar parts to those shown in Fig. 1 are represented by the same numbers. Referring to Fig. 9, the coupling 11 consists of two separable parts of which 115 represents the driving part having a sliding fit over the shaft 12 which drives 115 through the key 116 fitting into the shaft groove and the slot 117 in part 115. The bolt 118 is threaded into 115 but does not clamp the shaft 12. 119 represents a spring pressing against 115 the other end of the spring being secured to the shaft 12 and 120 represents two pins secured to 115. The spring 119 prevents the accidental sliding back of 115. 121 represents a flange on 115. Part 115 rotates the driven part 122 through the pins 120 fitting into two of twelve equally spaced holes in 122, there being a slight clearance between the holes and the pins to secure easy entrance of the latter. The cam 10 fits snugly on the taper fit of 122 and the nut 123 retains 10 in place, there being no key or other locking means between 10 and 122. The entire coupling 11 rotates on the end 124 of the stationary pin 125 having a hole 126 for inserting lubricants for the rubbing surfaces. The relative positions of the cam 10 and the shaft 12 are changed by gripping the flange 121, 125

sliding 115 back, allowing 12 to rotate a slight amount in the recess of 122 and then releasing 115 whereupon the spring 119 will cause the pins 120 to enter the next two diametrical holes in 122. In most cases two or three trials will give the desired cam position but if the nearest set of holes does not give the exact cam position desired the bolt 123 is loosened, the cam 10 is slightly tapped to loosen it from its 10 taper fit and turned the desired amount and again tightened in place by the nut 123. When the correct position of the cam 10 has been secured the bolt 118 may be clamped to the shaft to prevent easy disturbance of the 15 cam position.

Fig. 4 shows that the positions of 29 and 34 are respectively locked by 30 and 43 thus preventing movements due to vibration with resulting disturbance of the adjusted spinning 20 cycle. It is equally important to lock the position of 25 in 28 but similar locking means cannot be employed because of the inaccessibility to easily lock and unlock such means. Therefore I employ the locking 25 means shown in Fig. 10 whose description will be best understood when considered in connection with Fig. 6, the similar parts of both figures being represented by similar numbers. In Fig. 10, a hole 127 is drilled 30 as shown into the block 26 and a spring 127' placed into the hole forces the ball 128 against one of the V-shaped notches in the screw 25. The usually prevailing vibration will not rotate the screw 25 against the tension of the 35 spring 127', whereas hand movement of the knurled nut 49 in Fig. 4 will move 25 and with several of these notches the screw 25 can be moved from notch to notch with very small speed changes.

40 The operation of my controller in conjunction with the brush shifting device therefore results in speed changes having a substantially constant ratio to the controller received motion and the adjusting devices on 45 my controller enable operation with the ideal spinning cycle under various operating conditions without the interchange of new parts, neither of these advantageous operating characteristics being obtainable with any control 50 device of which I am aware. In addition my controller and brush shifting device may be built within the motor frame and base thus saving space and protecting the mechanism from the lint which prevails near textile machinery.

55 I have described my invention in connection with a spinning machine when spinning a filling wind but it will be obvious to those skilled in the art that my invention is equally applicable to the spinning of a warp wind.

60 I have described the operation of my controller with a Schrage type brush shifting alternating current motor but it is evident that my controller can be used to operate any motor or other device requiring a regulating

motion which is substantially proportional to that angle whose sine is proportional to the controller received motion. I have described preferred constructions of my controller and brush shifting device to give 70 proper speed control of spinning machines and the like, but it is obvious that various modifications may suggest themselves to those skilled in the art for accomplishing the same results without materially deviating 75 from my invention. Accordingly I wish it understood that my invention is not to be limited to the exact means shown and that such modifications as fall fairly within the true spirit and scope of my invention are intended 80 to be included within the scope of the appended claims.

What I claim as new and desire to secure by Letters Patent of the United States is:

1. In a regulating device, the combination 85 of a rotatable shaft, a movable member restricted to a linear movement, a second movable member restricted to a rotary movement, motion transmitting means between said shaft and the first mentioned movable member for transforming the rotary movement of said shaft into a linear reciprocating movement of said first mentioned movable member, and means actuated by the first mentioned movable member for rotating the second mentioned movable member through those angles whose sines are substantially directly proportional to the linear movement of the first mentioned movable member.

2. In a regulating device, the combination 100 of a plurality of rotatable shafts, a movable member restricted to a linear movement, a second movable member restricted to a rotary movement, motion transmitting means between said shafts and the first mentioned 105 movable member for combining and transforming the rotary movements of said shafts into a linear reciprocating movement of said first mentioned movable member, and means actuated by the first mentioned movable member for rotating the second mentioned movable member through those angles whose sines are substantially directly proportional to the linear movement of the first mentioned 110 movable member.

3. In a regulating device, the combination 115 of a rotatable shaft, a movable member restricted to a linear movement, a second movable member restricted to a rotary movement, motion transmitting means between said shaft and the first mentioned movable member for transforming the rotary movement of said shaft into a linear reciprocating movement of said first mentioned movable member, a driving member adapted to move freely on a surface of the first mentioned movable member in a direction perpendicular to the plane of the linear movement of said first mentioned movable member, and means 120 for securing said driving member to the sec- 125

ond mentioned movable member so that both rotate at the same angular velocity.

4. In a regulating device, the combination of a plurality of rotatable shafts, a movable member restricted to a linear movement, a second movable member restricted to a rotary movement, motion transmitting means between said shafts and the first mentioned movable member for combining and transforming the rotary movements of said shafts into a linear reciprocating movement of said first mentioned movable member, a driving member adapted to move freely on a surface of the first mentioned movable member in a direction perpendicular to the plane of the linear movement of said first mentioned movable member, and means for securing said driving member to the second mentioned movable member so that both rotate at the same angular velocity.

5. In a regulating device, the combination of a rotatable shaft, a movable member restricted to a linear movement, a second movable member restricted to a rotary movement, motion transmitting means between said shaft and the first mentioned movable member for transforming the rotary movement of said shaft into a linear reciprocating movement of said first mentioned movable member, a driving member adapted to move freely on a surface of the first mentioned movable member in a direction perpendicular to the plane of the linear movement of said first mentioned movable member, means for securing said driving member to the second mentioned movable member so that the axis of the driving member is substantially parallel to the rotation axis of the second mentioned movable member, and means for moving said driving member to change the distance between its axis and the rotation axis of the second mentioned movable member.

6. In a regulating device, the combination of a plurality of rotatable shafts, a movable member restricted to a linear movement, a second movable member restricted to a rotary movement, motion transmitting means between said shafts and the first mentioned movable member for combining and transforming the rotary movements of said shafts into a linear reciprocating movement of said first mentioned movable member, a driving member adapted to move freely on a surface of the first mentioned movable member in a direction perpendicular to the plane of the linear movement of said first mentioned movable member, means for securing said driving member to the second mentioned movable member so that the axis of the driving member is substantially parallel to the rotation axis of the second mentioned movable member, and means for moving said driving member to change the distance between its axis and the rotation axis of the second mentioned movable member.

7. In a regulating device, the combination of a rotatable shaft, a movable member restricted to a linear movement, motion transmitting means between said shaft and said movable member for transforming the rotary movement of said shaft into a linear reciprocating movement of said movable member, a driving member adapted to move freely on a surface of said movable member in a direction perpendicular to the plane of the linear movement of said movable member, a rotatable gear, means for securing said driving member to said gear so that both rotate at the same angular velocity, a rack in mesh with said gear, and means for restricting said rack to a linear movement.

8. In a regulating device, the combination of a plurality of rotatable shafts, a movable member restricted to a linear movement, motion transmitting means between said shafts and said movable member for combining and transforming the rotary movements of said shafts into a linear reciprocating movement of said movable member, a driving member adapted to move freely on a surface of said movable member in a direction perpendicular to the plane of the linear movement of said movable member, a rotatable gear, means for securing said driving member to said gear so that both rotate at the same angular velocity, a rack in mesh with said gear, and means for restricting said rack to a linear movement.

9. In a regulating device, the combination of two rotatable cams, two beams pivoted on each other, common resilient means secured to said beams, a projection secured to one of said beams in such a position that the action of said resilient means brings the other of said beams against said projection, means secured to one of said beams engaging the periphery of one of said cams, means secured to the other of said beams engaging the periphery of the other of said cams, a block pivoted on one of said beams, a movable member restricted to a linear movement, a connecting member between said block and said movable member, a driving member adapted to move freely on a surface of said movable member in a direction perpendicular to the plane of the linear movement of said movable member, a second movable member restricted to a rotary movement, and means for securing said driving member to the second mentioned movable member so that both rotate at the same angular velocity.

10. In a regulating device, the combination of two rotatable cams, two beams pivoted on each other, common resilient means secured to said beams, a projection secured to one of said beams in such a position that the action of said resilient means brings the other of said beams against said projection, means secured to one of said beams engaging the periphery of one of said cams, means

- secured to the other of said beams engaging the periphery of the other of said cams, a block pivoted on one of said beams, a movable member restricted to a linear movement, a connecting member between said block and said movable member, a driving member adapted to move freely on a surface of said movable member in a direction perpendicular to the plane of the linear movement of said movable member, a second movable member restricted to a rotary movement, means for securing said driving member to the second mentioned movable member so that the axis of the driving member is substantially parallel to the rotation axis of the second mentioned movable member, and means for moving said driving member to change the distance between its axis and the rotation axis of the second mentioned movable member. 5 70
- 10 11. In a regulating device, the combination of two rotatable cams, two beams pivoted on each other, common resilient means secured to said beams, a projection secured to one of said beams in such a position that the action of said resilient means brings the other of said beams against said projections, means secured to one of said beams engaging the periphery of one of said cams, means secured to the other of said beams engaging the periphery of the other of said cams, a block pivoted on one of said beams, a movable member restricted to a linear movement, a connecting member between said block and said movable member, a driving member adapted 15 75
- 20 to move freely on a surface of said movable member in a direction perpendicular to the plane of the linear movement of said movable member, a rotatable gear, means for securing said driving member to said gear so that both 25 80
- 25 rotate at the same angular velocity, a rack in mesh with said gear, and means for restricting said rack to a linear movement. 30 85
- 30 12. In a regulating device, the combination of a rotatable shaft, a movable member restricted to a linear movement, motion transmitting means between said shaft and said movable member for transforming the rotary movement of said shaft into a linear reciprocating movement of said movable member, a rotatable gear, a block resting against one 35 90
- 35 face of said gear, a driving member secured to said block, said driving member being adapted to move freely on a surface of said movable member in a direction perpendicular to the plane of the linear movement of said movable member, means for sliding said block relative to said gear to change the distance between the center of said driving member and the rotation axis of said gear, and means for securing said block to said gear so that both 40 95
- 40 rotate as a unit. 45 100
- 45 13. In a regulating device, the combination of a rotatable cam, a pivoted beam carrying a roller engaging the periphery of said cam, a block pivoted on said beam, said block having 50 105
- 50 an aperture, a movable member restricted to a linear movement, a second movable member restricted to a rotary movement, a threaded member screwed into the first mentioned movable member and protruding through said aperture, a shoulder secured to said threaded member and resting on said block, a gear secured to said shoulder, means for rotating said gear, a driving member adapted to move freely on a surface of the first mentioned movable member in a direction perpendicular to the plane of the linear movement of said first mentioned movable member, and means for securing said driving member to the second mentioned movable member so that both rotate at the same angular velocity. 55 110
- 55 14. In a regulating device, the combination of two rotatable cams, two beams pivoted on each other, common resilient means secured to said beams, a projection secured to one of said beams in such a position that the action of said resilient means brings the other of said beams against said projection, means secured to one of said beams engaging the periphery of one of said cams, means secured to the other of said beams engaging the periphery of the other of said cams, a block pivoted on one of said beams, a stationary member in spaced relationship to said block, and means carried by said block and adapted to come into contact with said stationary member at a predetermined distance between said block and said stationary member to prevent further movement of said block toward 60 115
- 60 said stationary member. 65 120
- 65 15. In a regulating device, the combination of a pin having two spaced apart shoulders, a rotatable circular sleeve located on said pin between its shoulders with a small axial clearance between the ends of the sleeve and the shoulders, said sleeve being threaded on its outer circular surface, a handle secured to said sleeve, an internally threaded member screwed on said sleeve in spaced relationship to said handle, a block secured to a surface of said internally threaded member, a second block adapted to slide on the first mentioned block with oppositely disposed surfaces of the second mentioned block respectively proximate to a surface of said handle and said surface of said internally threaded member, and means for moving the second mentioned block relatively to the first mentioned block. 70 125
- 70 16. In a brush shifting device for a dynamo electric machine, the combination of a stationary member provided with a shoulder and a circular surface extending from the shoulder to the end of said member, at least one brush yoke adapted to rotate on said circular surface, the length of said circular surface from the shoulder to the end of said member being such that the hub of a brush yoke projects slightly beyond the end of said member, a plate resting against the face of 75 130
- 75 17. In a brush shifting device for a dynamo electric machine, the combination of a stationary member provided with a shoulder and a circular surface extending from the shoulder to the end of said member, at least one brush yoke adapted to rotate on said circular surface, the length of said circular surface from the shoulder to the end of said member being such that the hub of a brush yoke projects slightly beyond the end of said member, a plate resting against the face of 80 135

the hub that projects beyond the end of said member, means for creating a pulling force between said plate and the end of said member, and means for simultaneously creating 5 a pushing force between said plate and the end of said member.

17. In a brush shifting device for a dynamo electric machine, the combination of two movable brush yokes, a member having 10 a circular surface, a shifting yoke adapted to move radially and angularly on said circular surface, engaging means between said brush yokes and said shifting yoke adapted to move said brush yokes during movement 15 of said shifting yoke, a stationary cam, and means secured to one end of said shifting yoke adapted to engage the contour of said cam for guiding said end of the shifting yoke in accordance with said cam contour.
18. In a brush shifting device for a dynamo electric machine, the combination of two movable brush yokes, a member having 20 a circular surface, a shifting yoke adapted to move radially and angularly on said circular surface, two driving pins with corresponding driving lugs secured to said yokes on opposite sides of said circular surface and adapted to move said brush yokes during movement of said shifting yoke, a cam having 25 two offset sections connected by a substantially circular section, means secured to one end of said shifting yoke adapted to engage the contour of said cam for guiding said end of the shifting yoke in accordance 30 with said cam contour, and means for removably securing said cam in either of two predetermined positions, one of said positions being so selected that the vertical axes of the offset sections of said cam are substantially 35 radial with respect to the center of said circular surface and the circular section of said cam is the arc of a circle whose radius is the center of one of said pins when said end of the shifting yoke is guided in accordance 40 with the contour of the circular section of said cam, and the other of said positions being so selected that the vertical axes of the offset sections of said cam are substantially 45 radial with respect to the center of said circular surface and the circular section of said cam is the arc of a circle whose radius is the center of the other of said pins when said end of the shifting yoke is guided in accordance 50 with the contour of the circular section of said cam.

19. In combination, a dynamo electric machine comprising a primary winding, two movable brush yokes, a member having a circular surface, a shifting yoke adapted to move 60 radially and angularly on said circular surface, engaging means between said brush yokes and said shifting yoke adapted to move said brush yokes during movement of said shifting yoke, a stationary cam removably secured in either of two predetermined posi-

tions, means secured to one end of said shifting yoke adapted to engage the contour of said cam for guiding said end of the shifting yoke in accordance with said cam contour, a source of alternating current, a switch for connecting said primary winding to said source to cause rotation of said machine in one direction, a switch for connecting said primary winding to said source to cause rotation of said machine in the opposite direction, means responsive to a predetermined position of one of said brush yokes with said cam in one of its predetermined positions for effecting the closing of the first mentioned switch, means responsive to a predetermined position of the other of said brush yokes with said cam in the other of its predetermined positions for effecting the closing of the other of said switches, and means for moving 70

said shifting yoke to bring the respective brush yoke to its predetermined position with said cam secured in either of its two predetermined positions.

20. A brush shifting device for a dynamo electric machine comprising two movable brush yokes, a member having a circular surface, a shifting yoke adapted to move radially and angularly on said circular surface, engaging means between said brush yokes and said shifting yoke adapted to move said brush yokes during movement of the shifting yoke, a stationary cam, means secured to one end of said shifting yoke adapted to engage the contour of said cam for guiding said end of the shifting yoke in accordance with said cam contour, a rotatable shaft, a movable member restricted to a linear movement, motion transmitting means between said shaft and said movable member for transforming the rotary movement of said shaft into a linear reciprocating movement of said movable member, a rotatable gear, means actuated by said movable member for rotating said gear through those angles whose sines are substantially directly proportional to the linear movement of said movable member, a rack in mesh with said gear, one end of said rack being adapted to impart its movement to the other end of said shifting yoke, and means for restricting said rack to a linear movement.

21. A brush shifting device for a dynamo electric machine comprising two movable brush yokes, a member having a circular surface, a shifting yoke adapted to move radially and angularly on said circular surface, engaging means between said brush yokes and said shifting yoke adapted to move said brush yokes during movement of the shifting yoke, a stationary cam, means secured to one end of said shifting yoke adapted to engage the contour of said cam for guiding said end of the shifting yoke in accordance with said cam contour, a plurality of rotatable shafts, a movable member restricted to a 120

125

130

- linear movement, motion transmitting means between said shafts and said movable member for combining and transforming the rotary movements of said shafts into a linear reciprocating movement of said movable member, a rotatable gear, means actuated by said movable member for rotating said gear through those angles whose sines are substantially directly proportional to the linear movement of said movable member, a rack in mesh with said gear, one end of said rack being adapted to impart its movement to the other end of said shifting yoke, and means for restricting said rack to a linear movement.
22. A brush shifting device for a dynamo electric machine comprising two movable brush yokes, a member having a circular surface, a shifting yoke adapted to move radially and angularly on said circular surface, engaging means between said brush yokes and said shifting yoke adapted to move said brush yokes during movement of the shifting yoke, a stationary cam, means secured to one end of said shifting yoke adapted to engage the contour of said cam for guiding said end of the shifting yoke in accordance with said cam contour, two rotatable cams, two beams pivoted on each other, common resilient means secured to one of said beams in such a position that the action of said resilient means brings the other of said beams against the last mentioned projection, means secured to one of said beams engaging the periphery of one of said rotatable cams, means secured to the other of said beams engaging the periphery of the other of said rotatable cams, a block pivoted on one of said beams, a movable member restricted to a linear movement, a connecting member between said pivoted block and said movable member, means carried by said pivoted block adapted to come into contact with said stationary projection at a predetermined distance between said block and said stationary projection to prevent further movement of said block toward said stationary projection, a driving member adapted to move freely on a surface of said movable member in a direction perpendicular to the plane of the linear movement of said movable member, a rotatable gear, means for securing said driving member to said gear so that both rotate at the same angular velocity, a rack in mesh with said gear, one end of said rack being adapted to impart its movement to the other end of said shifting yoke, and means for restricting said rack to a linear movement.
24. A brush shifting device for a dynamo electric machine comprising two movable brush yokes, a member having a circular surface, a shifting yoke adapted to move radially and angularly on said circular surface, engaging means between said brush yokes and said shifting yoke adapted to move said brush yokes during movement of the shifting yoke, a stationary cam, means secured to one end of said shifting yoke adapted to engage the contour of said cam for guiding said end of the shifting yoke in accordance with said cam contour, two rotatable cams, a movable member restricted to a linear movement, motion transmitting means between said rotatable cams and said movable member for combining and transforming the rotary movements of said rotatable cams into a linear reciprocating movement of said movable member, a rotatable gear, a block resting against one surface of said gear, a driving member secured to said block, said driving member being adapted to move freely on a surface of said movable member in a direction perpendicular to the plane of the linear movement of said movable member, means for sliding said block relatively to said gear to change the distance between the axis of said driving member and the rotation axis of said gear, means for securing said block to said gear so that both rotate as a unit, a rack in mesh with said gear, one end of said rack being adapted to impart its movement to the other end of the shifting yoke.
23. A brush shifting device for a dynamo electric machine comprising two movable brush yokes, a member provided with a circular surface, a stationary projection, a shifting yoke adapted to move radially and angularly on said circular surface, engaging means between said brush yokes and said shifting yoke adapted to move said brush yokes during movement of said shifting yoke, a stationary cam, means secured to one end of said shifting yoke adapted to engage the contour of said cam for guiding said end of the shifting yoke.

said shifting yoke, and means for restricting said rack to a linear movement.

25. A brush shifting device for a dynamo electric machine comprising two movable brush yokes, a member provided with a circular surface, a stationary projection, a shifting yoke adapted to move radially and angularly on said circular surface, engaging means between said brush yokes and said shifting yoke adapted to move said brush yokes during movement of said shifting yoke, a stationary cam, means secured to one end of said shifting yoke adapted to engage the contour of said cam for guiding said end of the shifting yoke in accordance with said cam contour, two rotatable cams, means for rotating one of said rotatable cams, a shaft secured to the other rotatable cam, a flanged member secured to said shaft, a second shaft, a flanged member adapted to slide longitudinally on the second shaft, engaging means between said flanged members adapted to engage each other at a plurality of relative angular positions of said flanged members, resilient means for biasing the slideable flanged member toward the other flanged member, two beams pivoted on each other, common resilient means secured to said beams, a projection secured to one of said beams in such a position that the action of said resilient means brings the other of said beams against the last mentioned projection, means secured to one of said beams engaging the periphery of one of said rotatable cams, means secured to the other of said beams engaging the periphery of the other of said rotatable cams, a block pivoted on one of said beams, a movable member restricted to a linear movement, a threaded member connecting said pivoted block and said movable member, said threaded member being so connected to said pivoted block and said movable member that the rotation of said threaded member changes the distance between said pivoted block and said movable member, means for rotating said threaded member, means carried by said pivoted block adapted to come into contact with said stationary projection at a predetermined distance between said block and said stationary projection to prevent further movement of said block toward said stationary projection, a rotatable gear, a block resting against one surface of said gear, a driving member secured to the last mentioned block, said driving member being adapted to move freely on a surface of said movable member in a direction perpendicular to the plane of the linear movement of said movable member, means for sliding the last mentioned block relatively to said gear to change the distance between the axis of the driving member and the rotation axis of said gear, means for securing the last mentioned block to said gear so that both rotate as a unit, a rack in mesh with said gear, one end of said rack being adapted to impart its movement to the other end of said shifting yoke, and means for restricting said rack to a linear movement.

26. A brush shifting device for a dynamo electric machine comprising two movable brush yokes, a member provided with a circular surface, a stationary projection, a shifting yoke adapted to move radially and angularly on said circular surface, engaging means between said brush yokes and said

shifting yoke adapted to move said brush yokes during movement of said shifting yoke, a stationary cam, means secured to one end of said shifting yoke adapted to engage the contour of said cam for guiding said end of the shifting yoke in accordance with said cam contour, two rotatable cams, means for rotating one of said rotatable cams, a shaft secured to the other rotatable cam, a flanged member secured to said shaft, a second shaft, a flanged member adapted to slide longitudinally on the second shaft, engaging means between said flanged members adapted to engage each other at a plurality of relative angular positions of said flanged members, resilient means for biasing the slideable flanged member toward the other flanged member, two beams pivoted on each other, common resilient means secured to said beams, a projection secured to one of said beams in such a position that the action of said resilient means brings the other of said beams against the last mentioned projection, a roller secured to one of said beams engaging the periphery of one of said rotatable cams, a roller secured to the other of said beams engaging the periphery of the other of said rotatable cams, a block pivoted on one of said beams, said block having an aperture, a movable member restricted to a linear movement, a threaded member screwed into said movable member and protruding through said aperture, a shoulder secured to said threaded member and resting on said pivoted block, means for rotating said threaded member, means carried by said pivoted block adapted to come into contact with said stationary projection at a predetermined distance between said pivoted block and said stationary projection to prevent further movement of said pivoted block toward said stationary projection, a rotatable gear, a block resting against one surface of said gear, a driving member secured to the last mentioned block, said driving member being adapted to move freely on a surface of said movable member in a direction perpendicular to the plane of the linear movement of said movable member, means for sliding the last mentioned block relatively to said gear to change the distance between the axis of the driving member and the rotation axis of said gear, means for securing the last mentioned block to said gear so that both rotate as a unit, a rack in mesh with said gear, one end of said rack being adapted to impart its movement to the other end of said shifting yoke, and means for restricting said rack to a linear movement.

In witness whereof, I have hereunto set my hand this 16th day of May, 1930.

JOHN I. HULL.

CERTIFICATE OF CORRECTION.

Patent No. 1,860,183.

May 24, 1932.

JOHN I. HULL.

It is hereby certified that error appears in the printed specification of the above numbered patent requiring correction as follows: Page 1, line 86, strike out the word "ring" and insert the same before "rail" in same line; page 5, line 71, for the misspelled word "spining" read spinning, and line 106, for "examinating" read examining; page 6, line 101, for "regulations" read regulation; page 11, line 26, claim 11, for "projections" read projection; and that the said Letters Patent should be read with these corrections therein that the same may conform to the record of the case in the Patent Office.

Signed and sealed this 12th day of July, A. D. 1932.

(Seal)
